DISTRIBUTION BOARD WITH FUSES
ADAPTED TO BE CUT OUT BY HAND

Fritz Driescher, Rheydt, Germany

Application February 2, 1932, Serial No. 590,404
In Germany June 1, 1931

1 Claim. (Cl. 200—114)

This invention relates to a cabling system serving particularly for several three-phase circuits with fuses adapted to be cut out by hand, in which each individual cable section is protected and can be cut out individually.

As compared with the known cabling systems, in which the handle fuses must always be completely removed when cutting out, the fuse carriers are according to the invention hinged like 10 switch levers on a base plate, so that the system forms a kind of combination of disconnecting switch and fuses. Each cut-out fuse carrier is preferably provided on the outer side with a T-shaped handle, rigidly fixed between two lugs 15 of the fuse carrier by means of a bolt. For switching in or out the fuses separately or jointly, a switching bar is employed according to the invention, which is provided on one side with a handle and on the other side with hooks arranged in pairs, some directed upwardly and others directed downwardly, and adapted to be hooked over the corresponding horizontal cross bar of the handles of the fuse carriers. In 20 a modified form of construction of the cabling system the cut out fuses, hingedly connected to the base plate like switch levers, belonging to one circuit are connected to a switch lever system by means of removable and fixable spring bolts in such a manner, that they can be switched 25 30 in or out singly or jointly. By this arrangement, in the event of fusing of one phase, this phase can be cut out separately, whereas the other phases remain operative; on the other hand however the entire system can, if desired, be actuated like a multiple pole switch. According to a further development of the invention the fusing of a fuse is indicated automatically at a distant observation desk by means of an optical or acoustic signal. For this purpose each fuse has two 35 40 lateral insulated contact springs, which contact with two contact bars of a signal circuit, when the cut-out fuse is switched in and when the wire fuses are bridged by another contact which bears under the action of a pressure spring on to an insulating pin. Further, for preventing shorting between the individual phases of a three-phase circuit, the current supply and return bars of two neighbouring circuits are mutually arranged symmetrically so that the axes of the unlike 45 50 phases lie at the corners of a triangle.

Two embodiments of the invention are illustrated by way of example in the accompanying drawings, in which:

Fig. 1 shows in front elevation a cable distribu-

tion board for two three-phase circuits, the cut-out fuses of one circuit being shown switched in and those of the other circuit omitted.

Fig. 2 is a side elevation of Fig. 1, one cut-out fuse being in closed and the other two in open position.

Fig. 3 is an end view of Fig. 1.

Fig. 4 shows the contacts of the signalling device.

Fig. 5 shows a single cut-out fuse cartridge in elevation.

Fig. 6 shows the switch bar in elevation.

Fig. 7 shows in front view a modified construction of the cable distribution board.

Fig. 8 is a side elevation of Fig. 7.

Fig. 9 is an end view of Fig. 7.

Fig. 10 shows in longitudinal section one of the releasable spring bolts.

On a base plate *a* made of insulating material three pairs of knife blade contacts 11—12, 13—14 and 15—16 are arranged on the current supply side and three pairs of knife blade contacts 17—18, 19—20 and 21—22 on the current consumption side. The knife blade contacts 12—18, 14—20 and 16—22 are connected by collector bars *R*, *S*, *T*. Supply leads *r*, *s*, *t*, laid in insulating tubes, extend to one end of the remaining knife blade contacts and delivery leads *r'*, *s'*, *t'* to the other end of these contacts. The terminals of the knife blade contacts 11—17 are situated in a higher plane than those of the remaining contacts, the supply and delivery wires *s*, *t* and *s'*, *t'* respectively being laid on both sides of the conductor bars *r* and *r'* directly on the base plate *a*. Thus the different phases are at the greatest possible distance apart, so that no short circuiting can occur. The individual phases are further separated by insulating walls *b*.

Every two companion knife blade contacts of a phase are bridged both on the supply side and on the delivery side by a cut-out fuse *c* adapted to be disconnected, oscillatably hinged on a bracket *d* below the lower contact knife blades of each phase and carrying contact clips *e* engaging over the contact blades, the cartridge *f* being fixed in said clips. This cartridge *f* preferably consists of a cylindrical casing in which the fuse wire *g* is arranged (Fig. 5) which is disposed in a lateral recess *h* of the casing. On the outer side of each fuse carrier *c* a T-shaped handle *i* is rigidly fixed between two lugs *i* by means of a bolt *k*, this handle serving for switching in and cutting out the cut-out fuse. The switching may be either effected directly by hand or through the intermediary of a switch bar *m*, pro-

vided on one side with a handle *n* and on the other side with six pairs of hooks *o*, some projecting upwards and the others downwards. The bar *m* enables the cut-out fuses *c* to be switched out and in individually or in common in that either the upper or the lower hooks *o* are hooked over the cross bars of the handle *l*.

An arrangement is further combined with the distribution board, which indicates the fusing of a cut-out fuse directly in the works or at some other observation place. For this purpose a bar *p* of insulating material is employed, which is provided with two contact bars *u*, *v*, connected to a battery circuit, in which an optical or acoustic signal is connected up. Each cut-out fuse has two lateral insulated contact springs *w*, *x* of different lengths, which, when the fuse is switched in, bear on the bars *u*, *v* and can be bridged by a contact *y*. The contact *y* is carried by an insulated rod *z*, extending into a bore *23* in the fuse *c* and encircled by a pressure spring *24*. From the lower end of the rod *z* a pin *25* extends, the lower bent and notched end *26* of this pin bearing on the fuse wire *g* in the recess *h*. When the fuse is intact, the contact *y* assumes the position indicated in Fig. 4 as soon as a fuse wire *g* fuses, the contact *y* is pressed against the contact springs *w*, *x* under the action of the spring *24* and closes the signalling circuit.

In the form of construction illustrated in Fig. 7, oscillatable levers *q* are mounted on the brackets *d*, their free ends being interconnected by a common switch bar *27*, carrying a handle *28*. Each lever *q* extends along the upper side of the fuses *c* between the lugs *i* and has a hole *29* at

this point. A sleeve *30* having a small bore at its outer end is tightly screwed into one of the lugs *i*, a bolt *32* encircled by a pressure spring *31* being inserted in this sleeve *30*. The bolt *32* has a small pin *33* and a knob *34*. The bore in the end *5* of the sleeve *30* is provided with a small recess *35*, through which the pin *33* can pass. Normally the bolt *32* assumes such a position that it passes through both lugs *i* of the fuse *c*. The distribution board can be operated and employed in a similar manner to a three-pole switch by actuating the handle *28* that is, the three-phase current net connected thereto can be switched in and cut out by one handle. Moreover, if one of the fuses has fused, the phase affected can be cut out separately, leaving the remaining phases in service. For this purpose the bolts *32* of the contact fuses are pulled back by means of the knobs *34* until their pins *33* are situated outside of their respective sleeves *30* and then slightly turned so that they remain in the position illustrated in Fig. 10. Thus, by pulling back the handle *28*, only the fused fuse is cut out, whereas the remaining phases remain operative.

I claim:

A distribution board with fuses arranged one above the other and adapted to be cut out by hand, comprising in combination a base plate, fuse carriers hingedly connected to said base plate, a switch bar, spring bolts detachably and fixably connecting said carriers to said bar to allow said carriers to be selectively switched in and out individually and jointly by said bar.

FRITZ DRIESCHER. 35.
